UNITED STATES PATENT OFFICE.

HARRY W. KNOWLTON, OF LOWELL, MASSACHUSETTS, ASSIGNOR TO KNOWLTON & NEWTON CO., INC., OF LOWELL, MASSACHUSETTS, A CORPORATION OF MASSACHUSETTS.

PICKER AIR INTAKE.

Application filed June 23, 1924. Serial No. 721,640.

To all whom it may concern:

Be it known that I, HARRY W. KNOWLTON, a citizen of the United States of America, and a resident of Lowell, in the county of Middlesex and State of Massachusetts, have invented certain new and useful Improvements in Picker Air Intakes, of which the following is a specification.

This invention relates to air intakes for pickers, the object of the invention being the provision of means whereby all the air delivered to the picker machinery will be drawn from the outside of the building thereby leaving unchanged the atmospheric conditions within the picker room.

The invention consists of certain novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents a diagram in plan of a picker room with the machines therein installed provided with a system for providing air therefor embodying the principles of the present invention.

Figure 2 represents a diagram of the same in elevation.

Figure 3 represents a vertical section of the mouth piece through which air is carried to the picker.

Figure 4 represents a transverse section of same on line 4, 4 on Fig. 3.

Figure 5 represents an elevation of the mouth piece through which air is carried to another portion of the picker machinery.

Figure 6 represents an end elevation of the same.

Figure 7 represents an elevation of the mouth piece through which air is carried to the breaker of the picker machinery.

Figure 8 represents a transverse section of the same on line 8, 8 on Fig. 7, and

Figure 9 represents a vertical section of a picker showing the mouth piece through which air is delivered to said picker.

Similar characters indicate like parts throughout the several figures of the drawing.

In the drawings 10, 10 are the side walls of a picker room and 11 the floor thereof.

Below the floor 11 are a plurality of pipes 12 all connected at one end to a main air supply pipe 13 one end of which extends through a side wall 10 and is bent downwardly as at 14 to shed water.

Near the open outer end of the main pipe 13 is a damper 15 which may be closed when the picker machinery is not in use.

When the picker machinery is in operation the damper 15 is opened, thereby permitting air from the outside of the building to be drawn through the pipe 13 and branch pipes 12 to the various parts of the picker machinery, such as the breaker 16, the first picker 17, and the finishing picker 18.

Each finishing picker 18 has a mouth piece 19 installed therein of the construction shown in Figures 3 and 4, the lower end 20 of which communicates through the floor 11 with a lateral extension 12* from one of the branch pipes 12.

This mouth piece has a discharge opening 21 near the top thereof which extends the entire width of the picker and beneath this opening 21 said mouth piece has two hollow triangular arms 22 which are adapted to deliver air to both sides of the picker, thus dispensing with the grid doors, usually used for this purpose.

Above the opening 21 and extending from the top of the mouth piece 19 is a plate 23 having at its outer end a vertical flange 24, said plate and flange forming a shield to prevent air entering the picker through the apron 25.

The beater 26 of each picker is provided with a shield 27 surrounding the opposite ends of its shaft 28, thereby preventing air from entering around said beater and the fan shaft 29 is provided with a similar shield 30 preventing air from entering the picker around said shaft.

These shields 27, 30 may be of any sim-

ple construction and it is believed therefore that detailed illustration thereof is unnecessary.

If more than one picker 18 is used in the system, another mouth piece 19 is provided for each picker.

As the first picker 17 has no apron 25 a mouth piece 31 is provided therefor similar to that shown in Figs. 5 and 6.

10 The lower end 32 communicates through the floor 11 with a lateral extension 32^x from one of the branch pipes 12 and its upper end is closed except at the sides thereof, said sides having the oppositely disposed 15 discharge openings 33 which deliver air to both sides of said picker 17.

Each branch pipe 12 is also provided with a lateral extension 34 which extends through the floor 11 and communicates with the 20 lower end of the mouth piece 35 and has a discharge opening 36 at the top thereof and side discharge openings 37 at opposite ends thereof.

These discharge openings 36, 37 are 25 adapted to deliver air to the breaker 16 both at the top and at both sides thereof.

The mouth piece 35 may be formed in one unit as shown in Figs. 7 and 8, or the vertical wall 38 may be omitted, one of the 30 imperforate walls of the machine being substituted therefor.

In the latter case the inclined wall 39 would be in a separate piece and secured to the machine thereby completing the discharge passage.

40 Heretofore the air passing through the picker machines has been taken from the picker room but this is very objectionable as this air is replaced by air from other rooms where it has been heated and humidified.

The cost of fuel to heat this air is considerable and this expense is saved where the air for the pickers is drawn from the outside of the building.

45 By using this system, not only is there a great economy in fuel but much better results are obtained as the quality of the work delivered from the pickers is greatly improved in view of the fact that it is possible to maintain a more even humidity in the picker room.

Better laps are obtained which are more even in weight, this being due to the fact 55 that the picker has delivered to it all the air that it requires and the supply is constant.

There is no necessity of heating the air delivered from this system no matter what 60 the temperature of the outside atmosphere may be.

It has been found that the improved quality of the laps is felt throughout the mill and very superior yarn is finally produced.

65 It is believed that the operation and many

advantages of the invention will be apparent without further description.

Having thus described my invention, I claim:

1. A picker air intake consisting of a 70 main supply pipe having an inlet through which air is adapted to be drawn from outside a building; and a mouth piece communicating with the inner end of said pipe and through which said air is adapted to 75 be discharged into said picker.

2. A picker air intake consisting of a main supply pipe having an inlet through which air is adapted to be drawn from outside a building; a mouth piece communicating with the inner end of said pipe and through which said air is adapted to be discharged into said picker; and means for closing said pipe when the picker is not 80 operating.

3. A picker air intake consisting of a main supply pipe having an inlet through which air is adapted to be drawn from outside a building; a mouth piece communicating with the inner end of said pipe and through which said air is adapted to be discharged into said picker; and means for regulating the amount of air entering said pipe.

4. A picker air intake consisting of a main supply pipe having an inlet through which air is adapted to be drawn from the outside of a building; branch pipes leading therefrom; and mouth pieces communicating with each branch pipe and through which said air is adapted to be discharged 100 into the pickers.

5. A picker air intake consisting of a main supply pipe beneath the floor of a building having an inlet through which air is adapted to be drawn from the outside of 105 said building; branch pipes leading therefrom; and mouth pieces communicating with each branch pipe and through which said air is adapted to be discharged into the pickers.

6. A picker air intake consisting of a main supply pipe having an inlet through which air is adapted to be drawn from the outside of a building; branch pipes leading therefrom; and a mouth piece communicating with each branch pipe and having an opening at the top thereof through which said air may be discharged into the picker.

7. A picker air intake consisting of a main supply pipe having an inlet through which air is adapted to be drawn from the outside of a building; branch pipes leading therefrom; and a mouth piece communicating with each branch pipe and having an opening at the top thereof and two hollow arms extending from one face through which said air may be discharged into the picker.

8. A picker air intake consisting of a main supply pipe having an inlet through

which air is adapted to be drawn from the outside of a building; branch pipes leading therefrom; and a mouth piece communicating with each branch pipe and having openings at the side thereof through which said air may be discharged into the picker.

9. A picker air intake consisting of a main supply pipe having an inlet through which air is adapted to be drawn from the outside of a building; branch pipes leading therefrom; and a mouth piece communicating with each branch pipe and having openings at the side and top thereof through which said air may be discharged into the picker.

10. A picker air intake consisting of a main supply pipe having an inlet through which air is adapted to be drawn from the outside of a building; branch pipes leading therefrom; a mouth piece communicating with each branch pipe and having an opening at the top thereof through which said air may be discharged into the picker; and a shield at the top of said mouth piece preventing the admission of air to said picker through the apron thereof.

11. A picker air intake consisting of a main supply pipe having an inlet through which air is adapted to be drawn from outside a building; means preventing the admission of air to said picker from the picker room; and mouth pieces communicating with said main supply pipe and through which said outside air is adapted to be discharged to the interior of said picker.

12. A picker air intake consisting of a main supply pipe having an inlet through which air is adapted to be drawn from the outside of a building; means preventing the admission of air to said picker from the picker room; and mouth pieces communicating with said main supply pipe through the floor of the picker room and through which said outside air is adapted to be discharged to the interior of said picker.

Signed by me at 746 Old South Bldg., Boston, Mass., this 20th day of June, 1924.

HARRY W. KNOWLTON.
